PLAY PEN PAD

Alice J. Stoner, Youngstown, Ohio, assignor to Frandee Corporation, Youngstown, Ohio, a corporation of Ohio

Filed Sept. 13, 1963, Ser. No. 76,575

Term of patent 7 years

(Cl. D92—2)

I claim:

The ornamental design for a play pen pad, as shown.
